Filed Mar. 16, 1959, Ser. No. 799,652

2 Claims. (Cl. 84—355)

This invention relates to a reed organ provided with a silent motor-driven blower supplying the necessary pressure air for musical playing thereof, thus dispensing with foot-pedals for generating the compressed air.

The main object of the invention is to provide an improved organ of the kind above referred to, wherein the unfavourable blower noises are minimized to an allowable degree, so that the musical sounds may be pleasantly enjoyed.

Another object of the invention is to provide a further improved organ of the kind above mentioned, wherein the required power for driving the blower is reduced to a minimum.

In order to fulfil the above described objects, the invention resides in an organ with motor-driven blower, comprising: a number of vibrating tongues or reeds arranged in a row; a first air chamber in communication with the atmosphere through an inlet opening; a second air chamber arranged just below said first air chamber, said first and second air chambers being adapted to communicate with each other through a number of normally closed air passage openings, when at least one of the latter is opened, each of said tongues being fixed to a wall of said first chamber and extending into the corresponding one of said passage openings; a spring-loaded and normally closed lid for each of the latter; keyboard means to operate each lid when the corresponding musical key is depressed; an upper air space in communication with said second air chamber; a lower air space in communication with said upper air space; a silent motor-blower assembly resiliently mounted within said second air space by a plurality of supporting arms with cushioning means and comprising a multi-stage blower and an electric motor direct-coupled to the latter; a dished shell covering said blower as a whole in a separated relation therefrom from above and directing the otherwise ineffective air flow downwardly, said shell being supported at its lower opening end on said supporting arms; and a stationary guide vane ring arranged between any two adjacent blower stages and fixed at its outer periphery on to said shell, the latter being provided with an upper central opening, through which the inner space of said shell communicates with said upper air space.

Various further and more specific objects, features and advantages of the invention will appear from the description given below, taken in connection with the accompanying drawings illustrating by way of example a preferred embodiment of this invention.

In the drawings:

FIGURE 1 shows a cross-section of the organ according to this invention;

FIGURE 2 represents a longitudinal section of part thereof, taken on the line I—I in FIG. 1.

Now, referring to the drawings, a preferred embodiment of this invention will be described more in detail.

In the drawings, 1 denotes the outer casing of the organ according to this invention, the said casing is opened at the bottom, and provided with a cover 2, which is pivoted at one side of the top of said casing. There are provided a number of keys 3 arranged in a horizontal plane, each of which is pivoted at its root portion by a pin 5 to a horizontal supporting bar 4 fixed to casing 1 so as to rock in a horizontal plane within certain limits. It will be clear from the foregoing that a corresponding

2

number of pins 5 to that of keys 3 are arranged in a horizontal row on the supporting bar 4. Keys 3 are resiliently urged to occupy their normal position by a same number of springs 7, which are arranged again in a horizontal row on a stationary supporting member 6 fixed to casing 1, the said member being arranged in the neighborhood of the cover-supporting upper end of said casing. Underneath the row of keys 3, there is arranged a first air chamber 8, which is fixed on a second air chamber 9. The first air chamber 8 is provided with an inlet opening 8', having a substantial length and passing through a side wall of the chamber. 10 denotes an adjustable cover adapted to adjust the air quantity introduced into the first air chamber 8, the upper end of the cover being hinged at the upper portion of the same side wall, as provided with said opening 8', of the first air chamber 8, while the lower end of said cover is kept at an adjustable height as desired by a suitable operating mechanism indicated at 10' by dotted lines to adjust the clearance between the upper wall 9a of second air chamber 9 and the lower end of said cover. A definite number of openings 12 corresponding to the number of keys 3 are provided in the upper wall 9a of second air chamber 9 and arranged in a horizontal row. A same number 25 of vibrating tongues 13 as keys 3 are arranged in a horizontal row, one end of each tongue is fixed on to the upper surface of wall 9a by a bolt 14, while the opposite end of said tongue is kept free, a substantial part of each tongue except the root portion thereof overlying the corresponding air passage or opening 12, which is normally closed by a movable cover or lid 15. These covers 15 are arranged in a horizontal row underneath the upper wall of second air chamber 9, each of said covers is provided recessed slots 16 and 17 at the opposite ends thereof, 30 respectively, the said slots being slidably engaged by pins 16' and 17', respectively. These pins project from the lower surface of upper wall of second air chamber 9 and arranged in two horizontal rows. Each cover 15 is urged to close the mating opening 12 by a leaf spring 18, one end of which is kept in contact with the lower surface of said cover 15, while the opposite end of the spring is fixed as shown. A connecting rod 19 slidably passes through the first air chamber 8 and mechanically connects the centre portion of key 3 with the end portion 40 of the corresponding movable cover 15. Sealing rings 20 and 21 made of felt are provided at the wall openings through which the connecting rod 19 slidably passes. The air chamber assembly 8, 9 is fixedly mounted on a couple of rigid supporting shelves 22, 22', which are arranged oppositely to each other and rigidly fixed to the side walls of outer casing 1. An inner casing 23 is arranged within the outer casing 1, the upper wall of the former being fixed to the lower surfaces of said shelves 22 and 22'. A connecting pipe 24 connects the inner space 50 of said inner casing 23 with that of the second air chamber 9 and one or more openings 25 are provided at the bottom wall of said casing 23. A separating wall 26 is provided horizontally at a suitable height within the inner space of said inner casing 23, thus separating the 55 said space into two, more specifically into upper and lower air chambers U and L, which communicate, however, with each other by an opening 27 provided at said separating wall. A motor-driven fan-assembly F, which will be described hereinbelow more in detail, is housed in the lower air chamber. The motor 28 comprises a rotor shaft 29 provided with upper and lower shoulders 29a, 29b; a rotor 31 mounted on the said rotor shaft; a stator core 32; a stator winding 33 mounted thereon; a motor housing 34 mounting said stator core 32; upper and lower end covers 35 and 35'; upper and lower bearing covers 36 and 37; upper and lower bearings 38 and 39, as in the 60 65 70

usual manner. From the periphery of said upper end cover 35, a plurality of supporting arms 40, 41 extend, each of the latter is fixed through the intermediary of a resilient cushioning member 46 or 47 on a seat 42 or 43 projecting from the inside wall surface of said inner casing 23, by means of a bolt 44 or 45, respectively. 48 and 49 denote lower and upper blower stages of the blower, the bosses 50 and 51 of the both stages are mounted on the rotor shaft 29 with a close fit and in a stack bear against the shoulder 30 on said shaft 29, while the upper surface of said upper boss 51 is pressed upon by a nut 52, which is tightly screwed on the upper screwed end of rotor shaft 29, thus the blower assembly 48, 49 being rigidly, but dismountably fixed on the last mentioned shaft. Blower blades 48', 49' or blowers 48, 49 are so constructed and arranged, that they compress air in operation, blowing it from inside to outside thereof. A dished shell 53 covers the blower assembly 48, 49 from above and is mounted fixedly on supporting arms 40, 41. The upper end wall of dished shell 53 is provided at its centre with an opening 54 positioned oppositely to said opening 27 provided in separating wall 26, the remaining end wall portion of said shell 53 being positioned in opposite relation to the blades 49' of the upper blower 49 with a small gap therebetween. A sealing means 55 shaped in a ring is inserted between both openings 27 and 54 in sealing engagement with wall 26 and shell 53. A stationary guide ring 56 is arranged between blower stages 48 and 49 and fixed at its outer peripheral bent edge to the inner wall surface of shell 53 by means of a plurality of bolts 57, the said ring 56 being provided with a number of guide vanes 56', which serves to guide air from the first blower stage to the second through central opening 58 in ring 56 and from outward to inward. In the upper and lower air chambers in the inside casing, there are a plurality of baffle plates 59, 60, 61 and 62, projecting in a vertically staggered manner from the inner wall surface of said casing 23. Thus, in operation, the air sucked by the blower assembly, as well as the same delivered from the latter, flows in a zigzag-shaped path, which serves to reduce the blower noises to a minimum. On the inside of the shell 53, noise-absorbing material 63 such as felt or the like is fitted, and in the similar manner the same material 64 is attached to the back surface of guide ring 56.

In operation, the motor 28 is energized and rotates the blower assembly 48, 49, thus air being induced from the upper air chamber within casing 23 through openings 27 and 54 to the upper blower stage 49 and driven by the vanes 49' from inside to outside. Then the air is guided through stationary guide vanes 56' from outside to inside and led to the lower blower stage 48. Thence, the air is driven by the blower blades downwards, guided by a plurality of baffles 61, 62, and finally discharged from the lower air chamber through opening 25 to the atmosphere, thereby the air pressure within the upper air space and the second air chamber 9 being kept reduced to that lower than the atmospheric. When the music player presses down any one of the keys 3, the corresponding lid or cover 15 is also depressed downwards by the connecting rod 19 against the action of spring 18, thus the corresponding opening 12 is opened, so that atmospheric air is induced through one or more openings 8' cut through the side wall of the first air chamber 8, and thence to the second air chamber 9, thereby the corresponding tongue 13 vibrates under the influence of the air flow passing round the latter and develops thus the desired musical sound as long as the key 3 under consideration is kept depressed by the player.

In such an organ, as above referred to, air flow for the playing music is developed by the motor-blower assembly. If appreciable blower noises should issue they would produce disturbing effects upon the musical sounds. Thus, it is imperative to minimize the blower noise as much as possible. This kind of noise increases with

increase of peripheral speed of the blower. On the other hand, the pressure in the second air chamber 9 and, thus the upper air space within inner frame 23, should be kept at a proper value lower than the atmospheric by a suitable difference, in order to vibrate one or more tongues 13 when the corresponding key or keys are operated. In the present embodiment of this invention, the blower is divided into two upper and lower stages, between which a guide ring is arranged as hereinbefore described for the purpose of operating the said two blower stages in series, and, thus to fulfil the above mentioned two necessary conditions. For a particular rotational speed and pressure drop, the radius of the two stage blower will be reduced to half, as compared with a mono-stage blower conventionally employed. With the blower radius reduced to the half, the noise level will be also reduced to the half, which in turn substantially suppresses the audible noises, because the human sense of hearing responds logarithmically to the intensity of sound vibrations. With use of blower or blowers of reduced diameter, the revolutions will be correspondingly reduced for a definite air delivery, so that the effect as set forth hereinabove may be advantageously attained. If the number of the blower stages is increased to 3 or more, the desired effects will be further increased. In this way, blower noises normally encountered with use of an organ provided with a motor-driven blower can be substantially minimized to such a degree, that they are scarcely felt by the human acoustic sense, thus the musical sounds played with the organ are kept undisturbed. Furthermore, by employing a two- or more stage blower, the power consumption can be more or less reduced in comparison with an organ using a mono-stage-blower, which operates naturally with higher peripheral speed of the blower blades, because the higher the tip speed the higher will be the mechanical loss of the blower. By employing a multi-stage blower, the width of the organ is also appreciably decreased.

In this invention, furthermore, the configuration of the dished shell covering the blower assembly from above is such that it guides and directs a part of the air driven by the upper stage of the blower, which is directed outwardly and would be otherwise ineffective, to flow downwards as an effective air stream, thus enabling the blower efficiency to be improved to still greater extent. On the other hand, the already mentioned provision of a sound absorbing material attached to the inner surface of the dished shell contributes naturally further to decrease the blower noises. The same material provided on the back of guide ring 56 contributes to obtain the same effect.

In view of the fact that the invention provides a highly improved organ with motor-driven blower, it will be understood that the foregoing description is to be considered not as limitative but merely illustrative, and that modifications of the invention are possible and are included within its scope as defined by the appended claims.

60 What I claim is:

1. A reed organ, comprising: an outer casing; a keyboard comprising a plurality of keys disposed in said casing for playing the organ; a plurality of walls defining first and second chambers in the casing, one of the walls having a plurality of openings providing communication between the chambers; a plurality of vibratory reeds arranged in a row on said one wall and each extending across one of said openings to vibrate thereat; a plurality of spring loaded lids normally closing the respective openings; means connecting the keys to the lids for selective operation by the keys to clear said openings and permit passage of air between the chambers through the cleared openings; spaced shelves in the casing supporting said walls; an inner casing supported suspended from said shelves in the outer casing.

and spaced from the outer casing; pipe means connecting the inner casing and the second one of said chambers and providing an air passage therebetween; a horizontal wall dividing the inner casing into upper and lower chambers communicating with each other through an opening in the horizontal wall; a motor-blower assembly carried by arms mounted on resilient members supported at interior sides of the inner casing in the lower chamber; a dished shell in the lower chamber covering said blower and spaced therefrom to direct air downwardly, said shell being supported on said arms; spaced vanes defining multiple stages of said blower rotatable in the shell; a stationary vane guide ring disposed between the rotatable vanes and secured to the interior of the shell, said shell having an upper central opening providing an air passage between the interior of the shell and said upper chamber through the opening in said horizontal wall; spaced baffle plates in the upper chamber defining a first tortuous air path and further spaced baffle plates in the lower chamber spaced from

10

15

20

said motor and defining second tortuous air path, said inner casing opening to the atmosphere at the end of said second air path, whereby air drawn under suction through the outer casing is substantially free from noises produced by the motor-blower assembly when leaving the opening in the inner casing.

2. A reed organ according to claim 1, wherein said shell and said guide ring are lined with sound absorbing material.
